UNITED STATES PATENT OFFICE.

CHARLES K. WARREN, OF THREE OAKS, MICHIGAN, ASSIGNOR TO THE WARREN FEATHERBONE CO., OF THREE OAKS, MICHIGAN, A CORPORATION OF MICHIGAN.

LEGGING.

1,324,484.

Specification of Letters Patent.

Patented Dec. 9, 1919.

Application filed May 22, 1918. Serial No. 235,930.

To all whom it may concern:

Be it known that I, CHARLES K. WARREN, a citizen of the United States, and a resident of Three Oaks, in the county of Berrien and 5 State of Michigan, have invented certain new and useful Improvements in Leggings, of which the following is a specification.

My invention relates to leggings, particularly to military leggings and to those constructed of more flexible material such as 10 canvas.

Leggings made of more flexible material such as canvas soon tend to wrinkle and collapse, particularly after they have become 15 wet. Usually stiffening strips are applied along the flap ends but these keep only the flaps and the adjacent sections of the legging straight, the other sections soon wrinkling, buckling and creasing. The object of 20 my invention is therefore to provide improved means for stiffening those sections away from the flaps without materially increasing the cost of manufacture. Usually leggings are built up of a number of vertical 25 sections seamed together, and in accordance with my invention I double seam the sections together and where required I insert stiffening strips of steel, "featherbone" or other suitable material, the strips together 30 with the overlapping seam sections producing stiffened bands which will keep the legging smooth and unwrinkled.

On the accompanying drawing which 35 illustrates my invention,

Figure 1 is a perspective view of a legging,

Fig. 2 is an enlarged sectional view on plane 2-2, Fig. 1, and

Fig. 3 is an enlarged sectional view on plane 3-3, Fig. 1.

The legging shown is built up of the four sections *a*, *b*, *c* and *d* of canvas or other flexible material, the sections *a* and *b* being the flap sections, which at their meeting 45 edges are constructed to provide pockets for stiffening strip structures 5 and 6 along which hooks 7 and eyes 8 are fastened to be received by the cord 9.

The outer edges of the flap sections are 50 seamed to the adjacent edges of the sections

c and *d* at *e* and *f* and the seam *g* secures together the other edges of the sections *c* and *d*. As clearly shown in Fig. 3, double seaming is preferably resorted to, the adjacent ends of the sections being folded and 55 overlapped, and sewn together at the ends along sewing lines *h* and *i*, these sewing lines being spaced apart a sufficient distance so that a stiffening strip 10 may be inserted through the seam from the top to the bottom of the legging. This stiffening strip 60 can be placed between any of the adjacent folds of the seam. In Fig. 3 it is shown between the outer folds of the seam, and the strip together with the three overlapping 65 fold sections will provide a stiffening band which is strong and rigid to keep the adjacent cloth from wrinkling, yet which is sufficiently pliable to permit the cloth to follow the curves of the ankle and leg so that the 70 legging can snugly fit. A stiffening strip could be placed in any or all of the seams, such strips being particularly desirable in the front and rear seams *f* and *e*. After insertion of the strips the upper and lower 75 edges of the legging are folded inwardly and down and secured by sewing lines *j* and *k* to form stiff hems *l* and *m* which will also assist in preventing wrinkling.

The stiffening strips may be of spring 80 metal or of other flexible material such as whalebone or "featherbone," and owing to the double seaming which provides four layers along the strengthening bands the stiffening strips can be very light so that 85 the weight, and the cost of the manufacture of the legging are not materially increased.

Having described my invention, I claim:

In a legging, vertical sections of fabric folded back along adjacent edges, the free 90 edge of one vertical section being interposed between adjacent plies of the other section and sewn together along the bends to form a multi-ply strengthening band, and a stiffening strip inserted between the sewing 95 lines and between adjacent plies.

In witness whereof, I hereunto subscribe my name this 13 day of May, A. D., 1918.

CHARLES K. WARREN.
